HANDLE FOR PLUMBING FITTINGS

Henry Marshall Stairs, Louisville, Ky., assignor to American Standard Inc., New York, N.Y., a corporation of Delaware

Filed Dec. 9, 1968, Ser. No. 14,849

Term of patent 14 years

Int. Cl. D23—01

U.S. Cl. 23—28

Fig. 1.

Fig. 2.

Fig. 3.

Fig. 4.

Fig. 5.

FIG. 1 is a top plan view of my handle for plumbing fittings embodying the new design;

FIG. 2 is an elevational view thereof;

FIG. 3 is a bottom plan view thereof;

FIG. 4 is a cross-sectional view taken along the plane marked 4—4 of FIG. 1;

FIG. 5 is another cross-sectional view taken along the plane marked 5—5 of FIG. 1.

I claim:

The ornamental design for a handle for plumbing fittings, substantially as shown.
